ELECTRIC ILLUMINATION

Kurt F. J. Kirsten, Seattle, Wash., assignor to
 Kirsten Lighting Corporation, a corporation of
 Washington

Application December 1, 1930, Serial No. 499,253

8 Claims. (Cl. 176—122)

In the art of electric illumination, gas-filled tubes in which ionization, arcing, and consequent illumination are effected have been used in many applications. In nearly all apparatus of this kind the gas-arc tube is very long in proportion to its diameter, and the excitation voltage is of the order of several thousand volts. In a few instances, very small gas-arc lamps have been used for voltages of the order of 120 for indicating purposes, but, as their capacity is usually very small, these have not been used as sources of light suitable for any large scale illumination.

In any gas-arc lamp in which there is no conducting liquid, the luminous arc is started by the introduction of a potential gradient at or between a pair of electrodes in the gas. This potential gradient causes ionization of the gas and causes an arc to exist between the electrodes. In the ordinary gas-arc lamp used for sign lighting and other purposes, the distance between the electrodes is of the order of one meter or more, and the potential is several thousand volts. If the tube is shortened so the distance between the electrodes is only a few millimeters, the arc may be started with a voltage as low as about 125 volts. If simple electrodes are used, the energy that can be accommodated by the lamp is extremely small and of little use in illumination. The gas-arc lamps mentioned above generally use single-phase alternating current.

The desirability of improvement in gas-arc lamps for low voltage is well known. In addition to the advantages of the high voltage gas-arc lamp, among which may be mentioned those of long life and low intrinsic brilliancy, the low voltage lamp can have the advantages of safety, freedom from step-up voltage transformers, increased luminosity for a given amount of material, and the feasibility of controlling the size and light output of the lamps between greater limits. Also, by making use of suitable gases and other elements, such as mercury, in lamps enclosed in glass transparent to ultra-violet light, the low voltage lamp is available for domestic and other uses where ultra-violet radiation is required.

My invention relates to gas-arc lamps of low voltage, which may be developed for high illuminating wattage. In common with other gas-arc lamps, my invention uses the so-called rare gases which can be caused to be conducting, or, as it is usually expressed, ionized and hence luminous

these, the gas neon may be mentioned as an example.

What my invention comprises is set forth in the following specification and succinctly defined in the appended claims.

Referring to the accompanying drawing:

Figure 1 shows certain elements of my invention in a limited embodiment;

Figure 2 shows my invention in its present preferred form;

Figure 3 is a sectional view of part of the elements shown in Figure 2; and

Figure 4 is a group of curves which assist in the explanation of my invention.

In my invention, the above mentioned limitations of the simple low voltage gas-arc lamps have been overcome by the use of a lamp of the kind shown in Figure 1. In Figure 1, two electrodes 1 and 2, of novel form, are sealed into a glass tube or other transparent insulating envelope 3 containing gas 4. The electrodes 1 and 2 are provided with terminals 5 and 6, respectively, brought out of the tube in any convenient manner. Voltage is applied to terminals 5 and 6 from any convenient source of energy of suitable characteristics. The electrodes 1 and 2 are helices or coils of wire terminating in adjacent ends 7 and 8. The ends 7 and 8 of the coils 1 and 2 are spaced a few millimeters apart. When the character and pressure of the gas in the tube are suitable, for example neon at between ten and twenty millimeters of mercury pressure, an arc can be started between the electrode ends 7 and 8 at about 125 volts. By increasing the voltage to about 160 volts, the electrodes are caused to be surrounded entirely by a luminous arc. The arc is caused to be distributed evenly along the electrodes by an adjustment of the voltage gradient from the ends 7 and 8 of the electrodes 1 and 2 to the terminals 5 and 6, such that the voltage difference between ends 7 and 8 of the electrodes 1 and 2 to the terminals 5 and 6 is just sufficient to overcome the increase of impedance due to the longer arc path. This voltage gradient is controlled by the design of the electrodes, which are made with sufficient impedance to accomplish the result desired.

If the voltage applied to the lamp is unidirectional, the negative electrode will glow, but the positive one will remain dark. If the applied voltage is alternating, it can be demonstrated by oscillographic observation that first one electrode and then the other glows in synchronism with the applied voltage. It can be shown also that

the glow does not begin until the instantaneous voltage of the applied alternating wave has exceeded the critical voltage of the lamp, and that the glow ceases when the instantaneous voltage has decreased to the critical cut-off voltage. This phenomenon is illustrated in Figure 4.

In Figure 4, there are three waves 11, 12, and 13, and an axis 10 representing voltage in ordinary three-phase relationship. Considering for the moment voltage wave 11, only, which we may assume represents the alternating voltage applied to the lamp shown in Figure 1, doubly hatched areas 14 represent the current that flows. The areas 14 above the axis 10 represent the current flowing when the gas at electrode 1 is luminous, and the areas 14 below the axis 10 represent the current flowing when the gas at electrode 2 is luminous. The resultant effect is a discontinuous and shifting light with appreciable flicker.

In order to overcome the objection of discontinuous light emission of the lamp shown in Figure 1, I have invented a lamp of the form shown in Figures 2 and 3. In Figures 2 and 3, there are a plurality of electrodes 21, 22, and 23, contained 20 in a glass or other transparent insulating sealed envelope 24, through whose walls current is conducted from terminals 25, 26, and 27. Gas 28 of suitable characteristics and pressure is also contained in the envelope 24. The electrodes 21, 22, 25 and 23 are supported, when necessary, by an insulated support 29. The electrodes 21, 22, and 23 terminate in an insulating holder 30, at which the ends 31, 32, and 33 of the electrodes 21, 22, and 23 are held a few millimeters apart. The arrangement of the electrodes in plan in the lamp is shown in Figure 3, which is a sectional view through Figure 2 at the points X—X in the direction indicated by the arrows.

In operation, the lamp shown in Figures 2 and 40 3 is connected by means of the terminals 25, 26, and 27 to any suitable source of three-phase alternating current. A voltage of about 105 volts between each of the terminals 25, 26, and 27 is sufficient to start arcing in the gas at the ends 31, 45 32, and 33 of the electrodes 21, 22, and 23. With somewhat greater voltage the gas surrounding all three of the electrodes becomes luminous. The proportions and shapes of the electrodes and the spaces between them are designed so that the increase of voltage between the ends 31, 32, and 33 50 of the electrodes 21, 22, and 23 where the current is a minimum, to the other ends of the electrodes 21, 22, and 23, where the current is a maximum, is graded so that the intensity of illumination of 55 the gas between the electrodes is substantially uniform throughout the length of the electrodes.

Referring again to Figure 4, the comparative performances of the lamps illustrated in Figures 1 and 2 will be explained. It was pointed out that 60 the illumination produced by the lamp shown in Figure 1, which is operated on single-phase current, was periodic and discontinuous, as was illustrated by the doubly hatched areas. With reference to Figure 2, the curves 11, 12, and 13 65 in Figure 4 represent the voltages between the terminals 25 and 26, 26 and 27, and 25 and 27 respectively, and the singly hatched areas 15 represent the currents caused to flow by these voltages. Since the light produced is more or less 70 proportional to the current flowing, the singly hatched areas 15 also represent light produced. In Figure 4 the performances of the lamps shown in Figures 1 and 2 have been superimposed for convenience but they may be considered as entirely separate phenomena. It is evident from 75

Figure 4 that currents flow between the respective electrodes 21, 22, and 23 of Figure 2 discontinuously, as between the electrodes 1 and 2 in Figure 1, but that the presence of a third electrode permits some current to flow all the time, since the impulses of current overlap. The result is continuous ionization of the gas in the lamp. Since the gas is ionized continuously, it is not necessary to reestablish the arc each half cycle as in the lamp shown in Figure 1, and therefore the lamp will operate at a lower voltage than one which has to be continually reionized. Also light is emitted continuously so there is no flicker.

The curves in Figure 4 are not intended to show quantitative relationships of voltages and currents with any degree of accuracy, but are intended merely to illustrate the nature of the phenomena encountered.

Likewise, it should be understood that the use of three-phase voltage and current in this instance is assumed for purposes of explanation only, and that any multi-phase alternating current system may be used, such as two, three, four, or six phase systems.

In Figure 2 the electrodes 21, 22, and 23 are 25 shown partly straight and partly coiled. The relative amounts of the straight and coiled portions can be varied to suit conditions, and they may be either coiled over practically the entire length or not coiled at all. Ordinarily the resistances of the electrodes 21, 22, and 23 are not 30 sufficiently high to cause them to be heated appreciably, and therefore the light emitted by the lamp ordinarily is that produced by the gaseous arc. However, if it be desirable, the resistances 35 of the electrodes can be of such values that the currents flowing therein will heat them to incandescence so that light is produced by both the gas in the tube and the heated electrodes. In certain embodiments of my invention the electrodes 40 are self-supporting, making the support 29 unnecessary.

I claim:

1. An electric lamp comprising a sealed transparent envelope containing gas, a plurality of 45 electrodes arranged symmetrically in said envelope, and held in position by a suitable insulated support, said electrodes being spaced so that when alternating multi-phase voltages of the order of 100 volts are applied thereto, current flow 50 and arcing will take place in said gas, said current flow and arcing in said gas being distributed over the surfaces of said electrodes in a manner determined by the relative spacing of said electrodes and their electrical impedances.

2. A three-phase alternating current electric lamp comprising a transparent sealed envelope containing gas, and three electrodes arranged to receive three-phase current through the walls of said envelope, said electrodes arranged so that 60 their ends farthest from their entrance through the walls of said envelope are spaced closely enough together to enable arcing to take place in said gas at low voltages, said electrodes also arranged in such a way that the distances between 65 them increase toward the ends where they enter through said walls of said envelope, and said electrodes having impedances appreciable in comparison with the impedance of the gas between them when said three-phase currents are flowing.

3. A multi-phase alternating current electric lamp comprising a transparent sealed envelope containing gas and a plurality of electrodes arranged to receive multi-phase current through the walls of said envelope, said electrodes ar- 75

5 ranged so that their ends farthest from their entrance through the walls of said envelope are spaced closely enough together to enable arcing to take place in said gas at low voltages, said electrodes also arranged in such a way that the distances between them increase toward the ends where they enter through said walls of said envelope, and said electrodes having impedances appreciable in comparison with the impedance of 10 the gas between them when said multi-phase currents are flowing.

10 4. The method of producing light electrically which consists of causing multi-phase currents to flow between elongated uniform metallic resistors 15 in a volume of gas in arc paths of various lengths in which the voltages impressed on said paths have graded values corresponding to their lengths.

15 5. An electric lamp comprising a sealed transparent insulating envelope containing an ionizable gas, terminals sealed in the envelope on which electrical potential may be impressed, electrodes in the envelope with ends connected to the terminals and other ends directed toward each other and terminating in spaced relation; each electrode being a uniform metallic resistor from 20 end to end and of such impedance as to cause current to flow between the electrodes in paths of various lengths in which the voltages impressed 25 have graded values corresponding to the lengths 30 of the paths.

6. A multi-phase gas arc lamp comprising a sealed, transparent envelope containing an ioniz-

able gas, a plurality of insulated electrodes arranged in the envelope to receive and transmit alternating currents; said electrodes being symmetrically arranged and each an elongated, uniform metallic resistor designed to effect an adjustment of voltage gradient therealong whereby current will flow between the said electrodes in arc paths of various lengths.

7. A gas arc electric lamp comprising a sealed, transparent envelope containing an ionizable gas, 10 elongated electrodes in diverging relationship, connected at their outer ends with a source of current and arranged in said envelope with their opposite ends closely spaced to permit arcing between them at low voltages; said electrodes being 15 uniform, metallic resistors thereby to effect a voltage gradient therealong whereby current will be caused to flow between them throughout their lengths in arcs of various lengths in which the voltages impressed have graded values corresponding to the lengths of the paths.

8. An electric lamp comprising a sealed, transparent envelope containing an ionizable gas, electrodes of coiled formation arranged in said envelope in co-axial alignment with their inner ends 25 closely spaced to permit arcing therebetween at low voltage and with circuit connections at their outer ends; said electrodes being uniform in material and resistance throughout their lengths to effect a voltage gradient from end to end whereby 30 the arc will be progressively distributed therealong.

KURT F. J. KIRSTEN.
